US0D1090420S

(12) **United States Design Patent** (10) Patent No.: **US D1,090,420 S**
(45) Date of Patent: ** Aug. 26, 2025

(54) **POWER BANK**

(71) Applicant: **SHENZHEN PANNIZHE TECHNOLOGY CO., LTD.**, Shenzhen (CN)

(72) Inventor: **Man Liao**, Shenzhen (CN)

(73) Assignee: **SHENZHEN PANNIZHE TECHNOLOGY CO., LTD.**, Shenzhen (CN)

(**) Term: **15 Years**

(21) Appl. No.: **29/913,181**

(22) Filed: **Sep. 28, 2023**

(51) LOC (15) Cl. **13-02**

(52) U.S. Cl.

USPC **D13/103**; D13/102

(58) Field of Classification Search

USPC D13/103, 107, 108, 110, 118, 119, 102

CPC H02J 7/0013; H02J 7/0042; H02J 7/0045; H02J 7/342; H01M 50/204; H01M 50/247; H02M 7/003

Primary Examiner — Michelle E. Wilson

Assistant Examiner — Charles Hwang

(57) **CLAIM**

The ornamental design for a power bank as shown and described.

DESCRIPTION

FIG. 1 is a perspective view of a power bank showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the power bank that form no part of the claimed design.

1 Claim, 8 Drawing Sheets
